UNITED STATES PATENT OFFICE.

EDWARD F. COOKINHAM AND DAVID B. COOK, OF FRANKFORT, NEW YORK, ASSIGNEES TO ACME ROAD MACHINERY COMPANY, OF FRANKFORT, NEW YORK, A CORPORATION.

SCARIFIER.

Application filed April 4, 1922. Serial No. 549,540.

To all whom it may concern:

Be it known that we, EDWARD F. COOKINHAM and DAVID B. COOK, citizens of the United States, residing at Frankfort, in the county of Herkimer and State of New York, have invented certain new and useful Improvements in Scarifiers, of which the following is a specification.

This invention relates to scarifiers particularly of that type used for breaking up old roads or the like preparatory to rebuilding or resurfacing the same, and is especially adapted for use as an attachment to a road roller or other tractor, the scarifier being attached to the rear of the road roller, and embodying a tooth bar which may be raised or lowered by a fluid pressure actuated means connected to the tooth bar.

The object of the invention is to generally improve the construction of such attachments, and particularly to increase the strength and rigidity of the parts and to improve the manner of connecting the same to the road roller.

25 A further object of the invention is to improve the means for holding the teeth in place.

A further object of the invention is to provide a pair of power cylinders, instead 30 of one as heretofore used, which results in decreasing the diameter of the cylinders and enables the tooth bar to be hung closer to the roller, and gives a more vertical thrust thereon, requiring less fluid pressure in the cylinders.

35 A further object of the invention is to provide a construction by means of which a broken tooth bar can be removed and replaced without disturbing the other parts.

40 Other advantages and improvements in the details of the structure will be apparent from the following description.

The invention is illustrated in the accompanying drawings in which Fig. 1 is a rear elevation of the attachment. Fig. 2 is a side elevation including also a part of the road roller. Figs. 3, 4 and 5 are side, end and top views of the blocks or arms which hold the teeth. Fig. 6 is a section on the line 6—6

50 of Fig. 1.

Referring specifically to the drawings, 30 indicates the rear end of a road roller or other traction vehicle to which the attachment is applied, the main support being provided by means of a pair of draw plates 31

which are flanged at the top and bolted to the under side of the body of the road roller, these plates standing vertically and being spaced apart to the extent permitted by the width of the roller. The lower rear corners 60 of the draw plates are provided with holes to receive a cross draw shaft 1, the draw plates being reinforced by plates 2 around the holes through which the shaft extends. The ends of the shaft 1 project at each side 65 beyond the draw plates, to receive clevises 3 which are free to turn on the shaft and form a pivot connection by means of which the tooth bar can be rocked up or down. The clevises 3 have jaws 3^a between which are received the stem flange of a T-section draw bar 4, which is securely bolted to the clevises. The tooth holding blocks or arms 5 are bolted directly to the head flanges of the draw bar 4, and these blocks are spaced along the bar 70 according to the number of teeth. Each block 5 consists of a flanged casting with a rear face 5^a through which the attaching bolts 5^b extend, and the front face having an upper seat 5^c and a lower seat 5^d, with a V- 75 shaped groove 5^e extending vertically in the seats, to receive the teeth 8. These teeth are hard steel bars, preferably square in cross section, and may be pointed at both ends, and they are held to the blocks 5 by means of 80 clips or caps 11 secured to the seats by bolts 12.

The top faces of the tooth blocks 5 are provided with shouldered seats on which is bolted a heavy angle cross piece 6 which 90 serves to stiffen the blocks and space the same apart, and in the angle of this cross piece are fitted and bolted a pair of thrust blocks 7 which in turn are pivoted as indicated at 17 to the lower ends of piston rods 95 8 the pistons of which operate in a pair of cylinders 15 the upper ends of which are pivoted as at 16 between the flanges 18 of a pair of upright brackets or standards 19 secured to a cross bar 20 at the rear end of 100 the roller frame. These two cylinders 15 are spaced apart, and fluid pressure is admitted or exhausted from opposite ends of the cylinders by means of pipes 33 connected to a pressure tank or other suitable source 105 of supply and controlled by suitable valves, the tank and valves being not shown.

In connection with the tooth bar, and to govern the depth to which the teeth will dig into the ground, a pair of gage wheels 110

40 are employed, one of which is located at each end of the bar, each wheel 40 is mounted on a stub axle 9 projecting from an angle block 9^a set in the angle of the cross bar 6 and securely bolted thereto. These gage wheels travel along the ground beside the teeth, and by adjusting the teeth the depth of cut may be varied. Any suitable means may be provided for raising and 10 lowering the tooth bar, and when raised or lowered it will rock on the shaft 1, to set the teeth into or out of the work, the gage wheels being carried by and being raised or lowered with the bar.

15 The clevises 3 permit free pivotal motion on the draw shaft 1 while transmitting a direct draft to the draw bar. The tooth blocks being bolted to the draw bar 4 and the cross piece 6 are positively spaced and rigidly 20 supported in position, and in raising or lowering or striking an obstruction all of the tooth blocks move as one unit. Furthermore, if one tooth block becomes broken it can be removed without disturbing the 25 others, since it is individually bolted to the supporting bars 4 and 6. The connection afforded by the blocks 17 to the piston rods permits the pressure to be applied directly to the tooth bar, and the cross bar 6 provides 30 improved means for this connection as well as for supporting the stud shafts 9, without the necessity for a shaft extending entirely across the attachment. The angle bar is also more rigid than a shaft would 35 be, and the gage wheels are more stiffly carried, without any danger of bending an axle extending entirely across between wheels. It will be noticed that practically all of the 40 parts can be cast, and machine work is largely unnecessary. By using a pair of power cylinders 15, spaced apart, the pressure is more evenly applied to the tooth bar, and cylinders of smaller diameter can be used, instead of a single cylinder of large diameter, whereby the pressure axis is brought 45

nearer to the body of the road engine, and the pressure can be exerted more nearly in a vertical line. It will be understood that when the draw bar is raised or lowered the cylinders 15 swing on their trunnions 16 to accommodate the lateral movement. 50

By using the depending draw plates 31 the line of draft is brought down close to the ground and consequently close to the work which is advantageous in transmitting the draft to the teeth and in holding the same in the ground. 55

We claim:

1. A scarifying attachment comprising a draw bar, a plurality of individual tooth blocks spaced along the bar, each block comprising a flanged casting with a front face secured to the bar, and a rear face having upper and lower seats, a tooth clamped against the seats, and a cross bar secured to 60 the tops of the blocks.

2. A scarifying attachment comprising a draw bar, individual tooth blocks secured thereto at their front ends, teeth clamped to the rear ends of the tooth blocks, a cross 70 bar secured to and extending across the top faces of the tooth blocks, and power means connected to said cross bar to raise and lower the same.

3. A scarifying attachment comprising a 75 draw bar having rear flanges, flanged tooth blocks bolted to said flanges, teeth clamped to the rear ends of said blocks, a flanged cross bar secured to the top faces of the tooth blocks, power means connected to the 80 cross bar to raise and lower the same, stub shafts fastened to the ends of the cross bar, and gage wheels mounted on the stub shafts.

In testimony whereof, we affix our signatures in presence of two witnesses.

DAVID B. COOK.

EDWARD F. COOKINHAM.
